UNITED STATES PATENT OFFICE.

DANIEL H. MURPHY, OF WEST HARTFORD, CONNECTICUT, ASSIGNOR TO AMERICAN WIREMOLD COMPANY, OF HARTFORD, CONNECTICUT, A CORPORATION OF CONNECTICUT.

TENSION DEVICE.

Application filed October 12, 1923. Serial No. 668,083.

To all whom it may concern:

Be it known that I, DANIEL H. MURPHY, a citizen of the United States, residing in West Hartford, in the county of Hartford

5 and State of Connecticut, have invented an Improvement in Tension Devices, of which the following description, in connection with the accompanying drawings, is a specification, like characters on the drawings

10 representing like parts.

This invention relates to tension devices for braiding machines.

15 Each braid-forming thread or filament used upon braiding machines is usually drawn from a thread mass that is supported by the braiding mechanism for rotation about a horizontal axis as the thread or filament unwinds.

20 It is important that tension be maintained upon each braid-forming thread or filament throughout the braiding operation, and in my patent 1,503,203 of July 29, 1924, for a tension device, I have disclosed, described and claimed a gravity tension bar that

25 rests upon the thread or filament mass to retard rotation of the mass, and the tension bar is shown as provided with weights which serve to vary the retarding effect of the tension bar.

30 It is found that the tension exerted upon the unwinding thread or filament by the tension bar of said application increases as the diameter of the thread or filament mass decreases, and the present invention, therefore, 35 contemplates simple means by which a gravity tension bar may be caused to exert a substantially uniform tension upon the unwinding thread or filament irrespective of the diameter of the thread or filament

40 mass.

An important feature of the present invention, therefore, resides in a tension bar that rests upon a yarn or thread mass to retard rotation of the mass, and having

45 weights for increasing the retarding effect of the tension bar, and in means for successively relieving the tension bar from the action of the different weights as the diameter of the thread or filament mass decreases.

50 The above and other features of the invention will be hereinafter described in connection with the accompanying drawings, which illustrate a good, practical form

In the drawings:

55 Fig. 1 is a perspective view of part of a braiding machine provided with the tension device of the present invention;

Fig. 2 is an enlarged side elevation with parts in section of a thread or filament mass 60 of Fig. 1 having the present tension device associated therewith; and

Fig. 3 is a sectional view of parts shown in Fig. 2 but shows the position occupied by these parts when the mass of thread or fila- 65 ment supply is nearly exhausted.

The tension device of the present invention may be used upon various types of braiding machines to tension the threads or filaments of either the outer or inner 70 thread supplies, and it may be used to tension thread, yarn, silk, wire or other forms of filaments that may be employed upon braiding machines, but hereinafter the term "thread" will be used in its broad sense to 75 designate these different kinds of filaments.

The braiding machine shown in part in Fig. 1 as employing the tension device of the present invention has a table 1 of circular contour, and rising from the table is 80 the fixed cam plate 2. Mounted centrally of the table 1 is the sleeve or tube 3 through which the braid 4 passes, and the lower end portion of the tube 3 may be tapered as shown toward the braiding point 5. The 85 tube 3 is supported from a fixed part of the machine frame by the arm 6, and the braid upon leaving the tube 3 may pass upwardly to take-up means, not shown.

Within the circular table 1 is mounted the 90 main revolving frame 7 which is of circular contour and is supported and rotated by means not shown. A ring 8 is mounted upon the frame 7 and is shown as electrically insulated therefrom by blocks 9, and 95 brackets 10 that support the outer thread supplies 11 are secured to and extend upwardly from the ring 8.

The thread supplies 11 may be wound upon tubes 12 and these tubes may be 100 mounted upon and supported by spindles 13, the ends of which may rest rotatably in slots 14 formed in the upper ends of the brackets 10. The thread 15 is shown as extending from the source of supply 11 under the bar 16 and through the guides 17 and 18, and then about a post 19 positioned at the pivot about which the lever 20 rocks.

Rocking movement is imparted to the lever 20 to raise and lower the thread 15 by a shoe 21 that slides in a tortuous slot within the cam plate 2, and the thread passes from 5 the post 19 to a slot 21^a at the opposite end of the lever 20 and then passes to the braiding point 5.

The inner thread carriers consist of frames 22 that are supported at their inner 10 ends by the trackway 23 and at their outer ends by shoes that extend into the slot 24 in the revolving frame 7, and the frames 22 travel in a direction opposite to the direction of travel of the outer thread carriers 15 11. Within the frames 22 are mounted the inner thread supplies 25 and the thread 26 is led from the supply 25 through suitable guides to the braiding point 5.

The construction so far described forms 20 no part of the present invention and has been shown and briefly described to make clear the application of the tension device of the present invention to the outer and inner thread carriers, but the present tension device is well adapted for use upon various types of braiding machines.

The tension device of the present invention, in the embodiment shown in Fig. 1, consists of a tension bar 27 which rests 30 upon the upper face of the thread mass 11 or 25 and the bar may be retained in place thereupon by upstanding posts 28. The arrangement is such that the tension bar 27 exerts a retarding or braking effect upon the 35 rotating mass as the latter is rotated by the unwinding thread.

It may be desirable to provide means for increasing or decreasing the retarding effect of the tension bar 27 to meet the requirements of different braiding conditions, and this may be accomplished by placing several weights upon the bar 27. In Fig. 1 these weights comprise bars 29 which may be similar to the tension bar 27, while in 45 Figs. 2 and 3 the weights are given the form of perforated disks 30. The weights conveniently are retained in place upon the tension bar 27 by providing the weights with apertures through which the posts 28 extend, 50 as will be apparent from the drawing, and the retarding effect produced by a tension bar may be varied as desired by varying the number of weights resting upon the bar.

As stated, it is found that the tension 55 exerted upon the unwinding thread by a tension bar increases as the diameter of the thread mass decreases, whereas it is desirable that the tension upon the thread should remain substantially constant. The present 60 invention contemplates simple means by which a substantially uniform tension will be exerted upon the thread, irrespective of the diameter of the thread mass, and to this end means is provided for successively relieving the tension bar 27 from the action

of the different weights as the diameter of the thread mass decreases.

This may be accomplished by various means, but in the construction shown, this is readily accomplished by constructing the 70 posts 28 so that they taper upwardly or decrease in size in the direction in which they extend, and the weights 29 and 30 are provided with apertures which decrease in size in the order in which they are stacked 75 upon the bars 27. As a result of this construction, the downward movement of the weights will be arrested successively by the posts 28, as will be apparent from Fig. 3, to thereby relieve the tension bar from the 80 action of the different weights as the diameter of the thread mass decreases.

What is claimed is:

1. In a braiding machine, the combination of a thread mass supported for rotation 85 about a horizontal axis to unwind the thread, a tension bar resting upon the thread mass to retard rotation of the mass, weights resting upon the tension bar to increase its retarding effect, and means for relieving the tension bar from the action of the different weights as the diameter of the thread mass decreases.

2. In a braiding machine, the combination of a thread mass supported for rotation about a horizontal axis, a tension bar resting upon the thread mass to retard rotation of the mass, weights resting upon the tension bar to increase its retarding effect, and means for arresting at spaced 95 intervals the downward movement of the weights to thereby relieve the tension bar from the action of the different weights as the diameter of the thread mass decreases.

3. In a device of the class described, the combination of a thread mass supported for rotation about a horizontal axis, a tension bar resting upon the thread mass to retard rotation of the mass, upwardly extending 100 guide posts for retaining the tension bar in place upon the thread mass, weights resting upon the tension bar to increase its retarding effect and adapted to be arrested successively in their downward movement by the posts to thereby relieve the tension bar from the action of the different weights as the diameter of the thread mass decreases.

4. In a braiding machine, the combination of a thread mass supported for rotation about a horizontal axis, a tension bar resting upon the thread mass, upwardly extending guide posts for retaining the tension bar in place upon the thread mass and decreasing in size in the direction in which they extend, weights resting upon the tension bar and having openings through which a post extends and adapted to be arrested successively in their downward movement by the increasing size of the posts to thereby relieve the tension bar from the 110 115 120 125 130

action of the different weights as the bar moves downwardly.

5. In a device of the class described, the combination of a thread mass supported for 5 rotation about a horizontal axis, a tension bar resting upon the thread mass to retard rotation of the mass, an upwardly extending guide post which decreases in size in the direction in which it extends, weights 10 resting upon the tension bar and having

openings through which the post extends and adapted to be arrested successively in their downward movement by the increasing size of the posts to thereby relieve the tension bar from the action of the different 15 weights as the bar moves downwardly.

In testimony whereof, I have signed my name to this specification.

DANIEL H. MURPHY.
